UNITED STATES PATENT OFFICE.

JAMES L. BENNETT AND OTTO C. SEVEBECK, OF SAN DIEGO, CALIFORNIA.

INTERNAL-COMBUSTION ENGINE.

1,150,411.

Specification of Letters Patent. Patented Aug. 17, 1915.

Application filed September 14, 1914. Serial No. 861,648.

To all whom it may concern:

Be it known that we, JAMES L. BENNETT and OTTO C. SEVEBECK, citizens of the United States, residing at San Diego, in the county of San Diego and State of California, have invented certain new and useful Improvements in Internal-Combustion Engines, of which the following is a specification.

10 Our invention relates to improvements in internal combustion engines, and has particular reference to such engines embodying a rotatable valve for controlling the supply and exhaust of gas and products of combustion, respectively, to and from the cylinder or cylinders of the engine.

An important object of the invention is to provide a rotary valve of simple construction, having an interior axially extending tubular exhaust shell, surrounded by a gas supply passage, whereby the gas is heated prior to entering the cylinder or cylinders and retains the exhaust tubular shell properly cooled.

25 A further object of the invention is to provide a valve of the above mentioned character, formed in an integral casting or construction, thus rendering the same inexpensive to manufacture, strong, and durable 30 and comparatively small.

Other objects and advantages of the invention will be apparent during the course of the following description.

In the accompanying drawings forming a part of this specification, and in which like numerals are employed to designate like parts throughout the same, Figure 1 is a horizontal sectional view through an engine embodying our invention with the valve in 40 elevation, Fig. 2 is a transverse sectional view taken on line 2—2 of Fig. 1, Fig. 3 is a longitudinal vertical sectional view taken on line 3—3 of Fig. 1, and, Fig. 4 is a transverse vertical sectional view taken on line 45 4—4 of Fig. 3.

In the drawings, wherein for the purpose of illustration is shown a preferred embodiment of the invention, the numeral 5 designates preferably vertically arranged cylinders, two in number, provided with a water jacket 6, extending over the upper closed end of the cylinders, as more clearly shown in Fig. 4.

Arranged between the cylinders 5, as more 55 clearly shown in Figs. 1 and 4, is a pref-

erably horizontal valve casing 7, having a main bore 8, and a contracted inner bore 9, as shown. The water jacket 6 extends through this valve casing, the ends of the valve casing being closed by removable heads 10, having openings or water jackets 11, in free communication with the water jacket 6. The heads 10 are secured to the valve casing 7 by means of bolts 12 or the like. Rotatably mounted within the valve casing 7 is a double walled tubular preferably integral valve 13.

As more clearly shown in Figs. 2, 3, and 4, this valve comprises an outer tubular shell 14, having its ends closed by heads 15, carrying a tubular spindle 16 and a solid spindle 17. The spindles 16 and 17 extend through openings 18 in the heads 10, as more clearly illustrated in Fig. 3. Extending axially within the outer tubular shell 14, in spaced concentric relation thereto, is an interior exhaust tubular shell 19 having its inner end closed, and coöperating with the outer tubular shell 14 for providing a gas supply passage 20, which is annular in cross-section. This gas supply passage 20 completely surrounds the periphery of interior exhaust tubular shell 19 and the inner end thereof, while having no communication with the interior of the same. The interior exhaust tubular shell 19 is rigidly connected and preferably formed integral with the tubular spindle 16 to rotate therewith, and projects inwardly therefrom with its interior in free communication with the interior of the tubular spindle, said tubular spindle discharging to the atmosphere or to the exhaust pipe or manifold.

As more clearly shown in Figs. 3 and 4, the outer tubular shell 14 is provided in its inner portion with a gas port 21, adapted to be successively brought into registration with combined gas and exhaust ports 22, formed upon the upper end of the inner walls of the cylinders 5, as more clearly shown in Figs. 1 and 4. As clearly shown in Fig. 4, an exhaust port 23 is formed in the inner portion of the valve, the same having free communication with the interior of the interior exhaust tubular shell 19, while having no communication with the gas supply passage 20. This inner exhaust port is adapted to be successively brought into registration with the ports 22.

As more clearly shown in Fig. 2, the outer

tubular shell 14 of the rotatable valve is provided with preferably diametrically oppositely arranged gas inlet ports 24, two in number, adapted to be successively brought into registration with a gas port 25, formed in the valve casing 17, the gas being supplied to the port 25 through a pipe 26, having communication with a carbureter (not shown). Attention is called to the fact that port 23 is disposed at ninety degrees from port 21, and ports 24 are also arranged at the same angle with relation to the port 21.

As more clearly shown in Figs. 1 and 3, the rotatable valve is provided with annular grooves 27, receiving packing rings 28. The numeral 29 designates ball bearings, arranged within the ends of the valve casing 17 and receiving the spindles 16 and 17, as shown. Secured to the spindle 17 is an extension or trunnion 30 carrying a worm wheel 31, engaged and driven by a worm wheel 32, secured to a vertical shaft 33. This vertical shaft is driven by the crank-shaft of the engine whereby the rotatable valve is driven at one-half crank-shaft speed.

The operation of the engine is as follows:—The engine being a four cycle engine, there are four strokes of the piston for each complete revolution of the valve. Assuming that the right-hand piston (not shown) is down, and the rotatable valve has just been moved to the position whereby the exhaust port 23 is in registration with the port 22, upon the up-stroke of the right-hand piston, the valve is further turned for closing the exhaust port. Upon the down stroke of the right-hand piston the valve is turned for bringing port 21 into registration with port 22, whereby the fuel is supplied into the cylinder, the valve having made one-half a revolution. The right-hand piston is now down and the valve is in a position to just about open the exhaust port of the left-hand cylinder, the left-hand piston being also down. Upon the next stroke, the right-hand piston comes up on compression, while the left-hand cylinder exhausts. Upon the next stroke, the right-hand piston moves down on its firing stroke, while the left-hand piston draws in a fresh charge. The right-hand piston is again down and the valve has made a complete revolution, the same being ready to open exhaust port for

the right-hand cylinder. This operation is of course repeated indefinitely.

We wish it understood that the invention is not restricted for use in connection with a four cycle engine as hereinabove described, and that the same may be employed in connection with any type of engine with which it is adapted to cooperate.

It is to be understood that the form of our invention herewith shown and described is to be taken as a preferred example of the same, and that various changes in the shape, size, and arrangement of parts may be resorted to without departing from the spirit of the invention or the scope of the subjoined claim.

Having thus described the invention, what is claimed is:

A rotatable valve for an internal combustion engine, comprising an outer tubular shell provided near its outer end with a gas supply port and near its inner end with a gas port whereby the gas is forced to travel for substantially the entire length of the outer tubular casing before passing into the cylinder of the engine; and an interior tubular exhaust shell having a substantially smaller diameter than the outer tubular shell and extending longitudinally thereof in spaced substantially concentric relation with its outlet end rigidly attached to the outer end of the outer shell outwardly of the gas supply port of the outer shell, the interior tubular exhaust shell having its outer end open and its inner end closed and spaced a substantial distance from the corresponding end of the outer tubular shell whereby the inner end of the inner tubular shell is completely surrounded by the passage formed by the inner and outer tubular shells, and the inner and outer tubular shells being provided with an exhaust passage leading into the inner closed end of the inner tubular shell whereby the heated exhaust gases are forced to travel for substantially the entire length of the inner tubular shell before reaching the atmosphere.

In testimony whereof we affix our signatures in presence of two witnesses.

JAMES L. BENNETT.
OTTO C. SEVEBECK.
